GRAIN DRIER

Charles D. Figley, Cedar Rapids, Iowa

Application August 31, 1959, Serial No. 57,388

Term of patent 14 years

(Cl. D13—1)

FIG. 3

FIG. 4

Fig. 1 is a front perspective view of a grain drier, showing my new design,

Fig. 2 is a front elevational view thereof with the doors in open position,

Fig. 3 is a rear elevational view thereof, and

Fig. 4 is a top view thereof.

The sides not shown in the drawings are substantially like those sides shown in Fig. 3.

I claim:

The ornamental design for a grain drier, as shown and described.
